Filed Oct. 29, 1963, Ser. No. 319,876

7 Claims. (Cl. 9—8)

This invention relates to a buoy.

An object of the present invention is to provide a buoy which will ride the surface of a body of water irrespective of any undulating movements which may be imparted to the buoy by the waves on such surface.

Another object of the present invention is to provide a buoy, which while riding a surface of a body of water, will support a sign-supporting standard when mounted thereon in a constant upright position regardless of any undulating movements which may be imparted to the buoy by the waves on such surface.

A further object of the present invention is to provide a buoy which is non-corrosive, which will require practically no maintenance during its life of use, and which is commercially practical.

Other objects and advantages of the present invention will become apparent from the following description taken in conjunction with the accompanying drawings, in which:

FIGURE 1 is an exploded view of the buoy according to the present invention.

FIGURE 2 is an assembled view of the buoy of FIGURE 1 and in position of use.

FIGURE 3 is a fragmentary view, with parts broken away and in section, of the base and stabilizer of the buoy according to the present invention, but showing the weight depending from the stabilizer.

FIGURE 4 is an enlarged fragmentary sectional view, with parts broken away, taken on the line 4—4 of FIGURE 2, but showing the weight housed within the stabilizer.

FIGURE 5 is a fragmentary plan view taken on the line 5—5 of FIGURE 4.

FIGURE 6 is a fragmentary exploded view of a part of the one-piece standard, the socket member, and the means operatively connecting the standard part to the socket member.

FIGURE 7 is an assembled view of the exploded structure of FIGURE 6.

FIGURE 8 is a partial assembled view of the exploded structure of FIGURE 6.

Referring to the drawings, the buoy, according to the present invention, comprises a base 10 which is fabricated wholly of a resilient material, such as rubber, natural or synthetic, or like material. The base 10 comprises a flat bottom 12, and rising from and extending about the perimeter of the bottom 12 is a wall 14. Also, rising from the bottom 12 is a hollow core 16 which is spaced from the wall 14, and has the upper end portion projecting above the upper end of the wall 14. A plurality of upstanding reinforcing ribs 18 are disposed externally in spaced relation about the core 16 and slope downwardly from the core 16 toward and merge into the flat bottom 12 at the jointure point of the flat bottom 12 with the wall 14. The space between the core 16 and the wall 14 forms a chamber which is open at its top. The core 16, as will be observed in FIGURE 4, is out of communication with the chamber.

A buoyant material 20, such as foam or air balls, is disposed within the chamber, and this material is insertable through the open top of the chamber. Of course, the chamber may be filled with air as the buoyant material, the air becoming compressed upon closing of the chamber by a cover to be subsequently described. As shown in the drawings, the chamber is filled with compressed air.

2

A socket member 11 which is fabricated wholly of a resilient material like nylon and the like, is disposed within and is fixedly supported in the core 16, the said material being of a lesser resiliency than the base resilient material.

A standard 9 is disposed so as to extend through the socket member 11 with a portion projecting out of and above the socket member 11 with a portion projecting out of and below the bottom 12 of the base 10.

Means is provided which operatively connects the standard 9 to the socket member. As shown in FIGURES 1 to 5, the standard 9 is in two parts, namely, an upper portion 32 serving as a flagpole, and a lower portion 45 serving as a supporting element. In the form illustrated in FIGURES 6 to 8, the standard is in one piece, and comprises an upper portion 32' serving as a flagpole, and a lower portion 45' serving as a supporting element.

Referring to the form of FIGURES 1 to 5, the socket member 11 includes a sleeve 13 and projecting outwardly from the lower end of the sleeve 13 is a flange 15. Also projecting inwardly from the upper end of the sleeve 13 is a flange 15'. A floor 17 extends across the interior of the flange 15' and is attached to or is integral with the flange 15'. A collar 19 rises from the floor 17. The collar is provided with external threads 21, the purpose of which will be subsequently described. The socket member 11 is disposed within the core 16 so that the flange 15 is received within a groove 23 formed in the lower end of the core 16 with the sleeve engaging the core 16 and the collar 19 opening out of the upper end of the projecting core portion. It is to be noted that the sleeve 13 has a plurality of ribs 13' which project externally therefrom and extend longitudinally along to its lower end portion, the ribs being received in cooperating grooves 16' formed in the core 16, this rib and groove structure serving to hold the sleeve from rotating within the core.

A removable cover 22 closes the open top of the chamber and has the outer boundary embracingly and sealingly secured to the upper end of the wall 14, the cover being fabricated wholly of resilient material of the type of resilient material of the base 10. Specifically, the cover 22 has a depending inturned skirt 24 extending about its perimeter, FIGURE 4, which releasably embraces a lip 26 extending about the upper end of the wall 14 and is sealingly secured to the wall 14. The cover 22 is provided with a central opening 28 which receives and extends snugly about the projecting upper end portion of the core 16 with the part of the cover constituting the wall of the opening seating upon and sealingly secured to the projecting core portion. As shown in FIGURES 1 to 3, the top of the cover is provided with spaced upstanding knobs, here shown three in number, the purpose of which is to support an assembly of the base 10, core 16, socket member 11, and cover 22, when superimposed thereon.

The upper portion 32 of the standard 9 serving as a flagpole is provided with means operatively connecting the portion 32 to the socket member 11. Such means comprises a coupler 34 which is conformably shaped to engage the collar 19 and surrounds and is fixedly carried by the upper portion 32 of the standard 9 serving as a flagpole, the coupler being provided with internal threads 36. The upper portion 32 of the standard 9 serving as a flagpole is disposed so that it extends in a perpendicular direction with respect to the base 10, FIGURES 1 and 2, with the coupler 34 engaging the collar 19. Actually, the threads 36 on the coupler 34 are in threaded engagement with the threads 21 on the collar 19. It is to be noted that the threads 36 and 21 on the coupler 34 and collar 19 respectively constitute

interengaging means on the coupler and collar. The upper portion 32 of the standard 9 comprises a hollow pipe fabricated of plastic material, and the upper end of the pipe 33 is closed by a plug 35 which receives and supports a stick 37 of a flag 39.

Means operatively connects the lower portion 45 of the standard 9 serving as a supporting element to the socket member 11. Such means comprises a cap 40 which is fabricated wholly of plastic material, the cap 40 having a flat top 41 and a skirt 42 extending about and depending from the perimeter of the top 41. The cap 40 is insertable through the lower end of the core 16 so that the top 41 engages the floor 17 of the socket member 11 and the skirt 42 engages the adjacent portion of the core 16. Means embodying a bolt and nut assembly and indicated generally by the numeral 44 secures the top 41 of the cap 40 to the floor 17 of the socket member 11, as is clearly shown in FIGURE 4.

Extending into and engaging the top 41 of the cap 40 and fixedly and dependingly secured to the skirt 42 of the cap 40 is the lower portion 45 of the standard 9 serving as a supporting element. The supporting element 45 takes the form of a hollow tube which is fabricated wholly of plastic material and which has a portion adjacent the upper end extending into and engaging the top 41 of the cap 40 and fixedly and dependingly secured to the skirt 42 of the cap 40.

A stabilizer 46 is disposed exteriorly about and is fixedly supported on the portion of the supporting element or tube 45 adjacent the lower end thereof. The stabilizer 46 comprises a pair of vertically-disposed semi-cylindrical shells 48 each fabricated wholly of plastic material, the shells being disposed so as to face away from each other and being fixedly secured on opposite sides of the tube 45. Extending about the part of the tube 45 between the portions adjacent the upper and lower ends thereof are a plurality of apertures 47 for the discharge of water therethrough.

A weighting means is operatively connected to the stabilizer 46. In the assembly illustrated in FIGURES 1, 2 and 4, the weighting material takes the form of a solid metal bar or a lead bar 50 which is housed within and carried by the part of the tube 45 defined by the stabilizer 46 or shells 48. In the assembly illustrated in FIGURE 3, the weighting material takes the form of a solid metal cylinder 52 such as a lead cylinder, the cylinder 52 being dependingly supported from an eye 54 projecting from the lower end of the tube 45.

An anchor 60 is operatively connected to the base 10. In the assembly as illustrated in FIGURES 1, 2 and 4, the anchor 60 is dependingly attached to an attaching element or split ring 61 carried by a shank 62 fixed to the bottom 12 of the base 10 by a flexible line 63. In the assembly as illustrated in FIGURE 3, the anchor 60, not shown, is attached by means of a flexible line 65 to an eye 64 which is dependingly carried by the cylinder 52.

With reference to the form illustrated in FIGURES 6 to 8, this form differs over the form of FIGURES 1 to 5 above described in that the standard 9' is in one part and includes the upper portion 32' serving as a flagpole and the lower portion 45' serving as a supporting element, the floor 17 extending across the interior of the flange 15' of the sleeve 13 of the socket member 11 being omitted, and the coupler 34' is slidably supported on the standard 9' and serves as the means for operatively connecting the standard 9' to the socket member 11'. By virtue of the standard 9' being in one part and the coupler 34' slidably therealong it is possible to lengthen or shorten the depth of the portion 45' serving as the supporting element.

As shown in FIGURES 6 to 8, the coupler 34' has an internal gasket 80 fabricated of soft rubber or pliable plastic material. In assembling, the standard 9' is inserted through the coupler 34', and the coupler 34' then slid along the standard 9' to the desired point, where-

upon the lower portion 45' of the standard 9' is inserted into the socket member 11' until there is a part projecting out of and beyond the bottom 12 of the base 10. At this point the internal threads 36' of the coupler 34' are brought into threaded engagement with the threads 21' on the collar 19', and the threads 36' of the coupler 34' are turned down tightly on the threads 21' of the collar 19', resulting in the gasket 80 grippingly engaging the adjacent portion of the standard 9' and firmly holding the standard 9' in position in the socket member 11'.

In operation, with the buoy of the present invention as illustrated in FIGURES 2, 3 and 8, the base 10 of the buoy rides the surface of a body of water A and supports the standard in a constant upright position regardless of any undulating movements which may be imparted to the base by the waves on such surface. Also, even if the sign-supporting standard is knocked down by a boat it will readily right itself as soon as the base of the buoy is freed from the object of impact. Of course, the flexible lines 63 and 65 connecting the anchor 60 to the cylinder 52 and base 10 respectively, are of such length as to permit the buoy to move without restraint to the undulating induced by the waves on the surface of the body of water.

It is to be noted that by virtue of the parts of the buoy of the present invention being fabricated of the defined materials the buoy is non-corrosive, requires practically no maintenance during its life of use, and is commercially practical.

What is claimed is:

1. A buoy comprising a base fabricated wholly of resilient material and including a flat bottom, a wall rising from and extending about the perimeter of said bottom, and a hollow core rising from said bottom and spaced from said wall and having the upper portion projecting above the upper end of said wall, the space between said core and said wall forming a chamber open at its top, the core being out of communication with said chamber, a buoyant material disposed within said chamber, a removable cover fabricated wholly of resilient material of the type of said base resilient material and closing the open top of said chamber and having the outer boundary embracing and sealingly secured to the upper end of said wall, said cover having a central opening receiving and extending snugly about the projecting upper end portion of said core with the part of the cover constituting the wall of said opening seating upon and sealingly secured to said projecting core portion, a socket member fabricated wholly of resilient material of a lesser resiliency than said base resilient material, said socket member being disposed within and fixedly supported in the upper end of the projecting core portion, a standard fabricated wholly of plastic material and disposed so as to extend through said socket member with a portion projecting out of and above said socket member and serving as a flagpole and with a portion projecting out of and below the bottom of said base and serving as a supporting element, means operatively connecting the standard to said socket member, a stabilizer fabricated wholly of plastic material and disposed about and fixedly supported on the portion of said standard serving as a supporting element, and weighting means operatively connected to said stabilizer.

2. The buoy according to claim 1 which includes in addition an anchor operatively connected to said base.

3. The buoy according to claim 1 wherein said stabilizer embodies a pair of vertically-disposed semi-cylindrical shells facing away from each other and fixedly disposed on opposite sides of the portion of said standard serving as a supporting element.

4. The buoy according to claim 1 wherein the means operatively connecting the standard to said socket member comprises a coupler on the portion of said standard

serving as a flagpole releasably engageable with a collar rising from said socket member.

5. The buoy according to claim 1 wherein the means operatively connecting the standard to said socket member comprises a coupler on the portion of said standard serving as a flagpole releasably engageable with a collar rising from said socket member, and a cap fabricated wholly of plastic material dependently engageable with a floor formed on said socket member, and fixedly embracing the upper part of the portion of said standard serving as a supporting element, and means securing the top of said cap to the floor of said socket member.

6. The buoy according to claim 1 wherein the portion of said standard serving as a supporting element is a hollow tube, and wherein the weighting means embodies a solid metal bar housed within and carried by the part of the tube defined by the stabilizer.

7. The buoy according to claim 1 wherein the weighting means embodies a solid metal cylinder dependently supported from the lower end of the portion of said standard serving as a supporting element.
